Application January 14, 1948, Serial No. 2,230

18 Claims. (Cl. 200—136.3)

1

The present invention is directed to a control device whose control point is adapted to be shifted by a clock mechanism. More particularly the invention is directed to a clock thermostat that is adapted to maintain one temperature during the day and a reduced temperature during the night or during periods of non-occupancy.

An object of the invention is to provide a control device having a clock mechanism for shifting the control point between two adjustable values.

Another object is to provide a time adjusted control device having means extending outside the housing for the device for setting the high and low control points in a convenient manner.

A further object is to provide a clock thermostat in which the day and night temperature settings are selected by a pair of levers having their ends extending beyond one end of the instrument case and cooperating with a temperature scale at the end of the case.

A further object of the invention is to provide a clock driven cam having an adjustable raised portion for shifting a member between adjustable abutments to vary the control point of a condition responsive device.

Another object is to provide an adjustable cam, the raised portion of which may be adjusted to cover a maximum arc that is more than twice the minimum possible arc.

Another object is to provide a novel cam for shifting control point between day and night settings that is rotatable with a twenty-four hour dial and has pointers adjustable with respect to the dial to determine the times at which the control point will be shifted.

Other objects will be apparent from the following written description and claims, and from the drawings, in which

Figure 1 is a face view of a clock thermostat with certain parts broken away and with the mechanism in a position to control at a selected reduced temperature;

Figure 2 is a bottom view of the instrument shown in Figure 1 with certain parts broken away and certain parts in section;

Figure 3 is a fragmentary view of the mechanism illustrated in Figures 1 and 2 with the instrument base eliminated and with the parts in a position to control at a selected elevated temperature;

Figure 4 is a view of the composite cam adjusted to provide the maximum effective raised profile, and

Figure 5 is an exploded view of the twenty-four hour dial and cam assembly.

2

The instrument to be described is a clock type of room thermostat adapted to be mounted on the wall of a room for controlling the supply of heat to the room. The device controls the supply of heat to maintain higher temperatures during the day and lowered temperatures during the night or periods of non-occupancy. Provision is made for selecting the times at which the control point is reduced in the evening and raised in the morning. Provision is also made for selecting the desired day and night temperatures. A feature of the described device is that the day and night temperature selecting levers extend outside the housing of the device and may be adjusted to maintain a constant temperature when the occasion arises.

Referring now to the drawing, the clock thermostat has a generally flat and rectangular base 10 which is adapted for mounting on a vertical wall surface of a room. The base 10 is recessed on its underside to facilitate wiring the device and also to accommodate the temperature adjusting levers as will hereinafter appear. A cover or screen 11 in the form of an inverted box with its open side resting against the base 10 encloses the clock mechanism, thermostat, and adjusting mechanism. The top and bottom surfaces of the screen 11 are provided with a plurality of openings 12 to permit room air to circulate through the screen 11 and over the thermostatic element. The openings 12 are also beneficial in conducting heat away from the clock mechanism which is preferably of the type operating on regulated frequency alternating current. The screen 11 is provided with suitable projections that enter openings in the base 10 so that the cover may be fixed in place by tightening a pair of screws 13 extending through the upper and lower edges of the base. An opening in the front face of the screen 11 is covered with a clear plastic dial 15 which carries the clock numerals and through which the clock hands are visible.

Since, for the purposes of the present disclosure, the clock mechanism may be of any type either spring wound or electric, no details of the mechanism have been shown and it is illustrated as being contained in a clock housing 16 suitably secured to the base 10. Besides driving the clock hands the clock mechanism also drives a twenty-four hour dial 18 through a suitable gear train 19 terminating in the gear 21 which is rigidly attached to the dial 18 and rotatable therewith. An adjustable cam assembly generally indicated at 23 is rotatable with the dial 18 and together with the dial 18 is rotatable on a pin 25 which

is carried on an extension 26 of the housing 16 of the clock mechanism. The cam and dial assembly will be described in detail hereinafter.

A wheel 28 extends through one edge of the base 10 and serves to permit adjustment of the clock hands as well as the twenty-four hour dial 18.

The external appearance of the device including the base 10 and the screen 11 is covered in my co-pending design application Ser. No. D. 138,361, filed April 14, 1947, now Patent Des. 151,905.

The base 10 is made of suitable insulating material such as molded Bakelite and carries brackets 30 and 31 which are electrically connected to the binding screws 32 and 33. The bracket 30 carries an adjustable contact 35 and the bracket 31 carries an adjustable contact 36. A bracket 38 mounted on the lower edge of the base is electrically connected to a terminal screw 39 and has an upstanding portion 40 to which is attached a resilient blade 41. A contact arm 42 is secured to the blade 41 adjacent the bracket 40 and extends upwardly to carry a movable contact 43 that cooperates with the stationary contact 36. The blade 41 also extends upwardly to carry a contact 44 that cooperates with stationary contact 35. The blade 41 and arm 42 are formed so that the portion of the blade 41 between the bracket 40 and its connection to the arm 42 biases contact 43 into engagement with the stationary contact 36. The upper extension of the blade 41 passes through an opening in the arm 42 and is biased lightly into engagement with the right hand edge thereof. Stationary contact 35 is adjusted so that it will engage the contact 44 and press the blade 41 back slightly with respect to the arm 42 before contact 43 can engage the contact 36. This contact structure, together with the thermostatic element to be described later, is the subject of my co-pending application, Ser. No. 681,442, filed July 5, 1946, now Patent Re. 22,998.

As mentioned above, both sets of contacts are biased to closed position by the resilient blade 41. The contacts may be separated by a U-shaped bimetallic thermostatic element 46 that is adapted to engage an abutment 47 on the upper extremity of the contact arm 42. The bimetal element 46 is pivoted on a pin 48 extending upwardly from the bracket 38. The temperature at which the element 46 will separate the contacts depends on the position of the upper end of the right-hand leg of the element. A pivot pin 50 extends outwardly from the base 10 and has pivoted thereto a member 51 that is connected to the right hand leg of the bimetal 46 by a link 52. A member 54 is also pivoted on the post 50 and normally moves with the member 51. However, an eccentric 55 pivoted in the member 54 and engaging the member 51 adjusts the relative angular position of the two members about the pivot pin 50 for calibrating the device. A pin 57 carried by the left-hand end of the member 54 extends through an opening 58 in the base 10 and is adapted to engage portions of a day temperature adjusting arm 60 and a night temperature adjustment arm 61 which are pivoted in the base 10 on a bolt 63. A pair of friction washers 64 are interposed between the arms 60 and 61 and between a spring washer 65 and the head of the bolt 63. The washers 64 are provided with ears 66 that engage a portion of the base 10 to prevent rotation thereof. The right hand extremity of the arms 60 and 61 extend through an opening in the base and underneath a scale plate 70 carried at the

right-hand end of the base 10. The indicia on the plate 70 are located so as to be visible when the screen 11 is in place and provide for adjustment of day and night temperatures without removing the screen 11. Screws 71 and 72 are adapted to lock the arms 60 and 61 to the plate 70 to prevent unauthorized adjustment of temperature settings if desired.

Without reference to the function of the cam and cam follower to be described below, it will be seen that the resilient blade 41 tends to maintain the contacts in closed position and through the arm 42 and its abutment 47 tends to move the bimetal element 46 in a clockwise direction and places the link 52 in compression to move the member 51 and member 54 in a clockwise direction so that the pin 57 is in engagement with the day temperature adjusting arm 60, as shown in Figure 3. If the clock mechanism housing 16 together with the dial 18 and cam assembly 23 is removed from the base 10, the thermostat will be controllable by the day temperature adjusting arm 60, since it is only by engagement of the pin 57 on member 54 with this arm that the bimetal element 46 will be able to expand to move the contacts to open position against the action of the resilient blade 41.

A cam follower 75 is also pivoted on the post 50 and it is provided with a roller 76 that engages a cam 23. The cam follower 75 is provided with a lower extension 78 that extends generally parallel to the member 54 and is adapted to engage a screw 79 carried by member 54. A spring 81 extends between the portion 78 of the cam follower 75 and an extension 83 of the member 54 and serves to bias the cam follower to a position where the extension 78 engages the screw 79. The purpose of the abutment between the extension 78 and the last member 54 is to limit relative rotation therebetween and to eliminate the biasing effect of the spring 81 on the member 54 when the roller 76 of the cam follower 75 is out of engagement with cam assembly 23, thus permitting the resilient plate 41 to bias the member 54 into engagement with the day temperature adjusting arm 60 as above described. The screw 79 is adjusted so that the roller 76 will not engage the low portion of the cam assembly 23 when the day temperature setting arm 60 is raised to the highest possible temperature setting. Adjustment of the screw 79 should also be such that when the roller 76 of the cam follower 75 is on the high part of the cam and the night temperature adjusting arm 61 is at its lowest possible setting, there will be some clearance between the screw 79 and the extension 78 of the cam follower to assure that the pin 57 is held in engagement with the arm 61. Thus it will be seen that the difference in radii between the low and high portion of the cam should be sufficient to move the cam follower 75 through an angle slightly greater than the possible angular movement of the member 54 as determined by the maximum temperature setting of the arm 60 and the minimum temperature setting of the arm 61. With this construction, no great accuracy of the cam profile is required. Consequently the cam disks can be made by simple stamping operations.

As mentioned above, the dial 18 and the cam assembly 23 are rotatable on a pin 25 carried by the extension 26 of the clock motor housing 16. Cam assembly 23 comprises four similarly shaped disks 85, 86, 87 and 88, as shown in Figures 4 and 5. The lower disk 85 is fixed to a sleeve 90

that is directly rotatable on the pin 28. The sleeve 90 is fluted as at 91 to cooperate with complementary projections 92 on a pointer 93 which cooperates with the dial 18 to indicate the time at which the thermostat will be adjusted from the high temperature setting to the low temperature setting. The upper cam disk 88 has a sleeve 95 fixed thereto which pivots on the sleeve 90 attached to the disk 88. The sleeve 95 has projections 96 thereon that cooperate with complementary recesses 97 formed in a sleeve 97 attached to a pointer 98 which cooperates with the dial 18 to indicate the time at which the temperature setting will be shifted from that established by the adjusting arm 61 to that established by the adjusting arm 60. The sleeve 98 is threaded at its upper end to cooperate with a nut 100 that may be tightened to draw the cam disk and the pointer toward the dial 18 to lock the parts to the dial so that they will be rotated as a unit by the clock motor. A spring washer 102 is interposed between the disk 88 and the dial to assist in so locking the parts together. The axially projecting lengths of the sleeves 95 and 97 as well as of the projections 96 are such that sufficient axial movement is permitted to allow drawing the cam disk 88 and the pointer 98 tightly against the dial 18 as the nut 100 is tightened on the sleeve 98. Likewise the cooperation between the fluting 91 in the sleeve 90 and the projection 92 on the pointer 93 is such that axial movement of the parts is permitted as the nut 100 is tightened on the sleeve 98.

The cam disk 86 is provided with a short lateral projection 104 that cooperates with an arcuate opening 105 in the disk 85 to limit pivotal movement between the two disks. With the projection 104 in one end of the slot 105 the contours of the two disks are coincident while at the other end of the permitted movement the raised edges of the high parts of the cam cover an extended arc but no gap is permitted therebetween. The disk 86 is provided with an arcuate opening 106 that cooperates with a projection 107 on the disk 87 and likewise limits relative rotation between these two disks. Disk 87 is also provided with a projection 108 that cooperates with a radial opening 109 in the disk 88 for a similar purpose. The position of the lower disk 86 relative to the upper disk 88 and the position of the cam assembly relative to the dial 18 may be adjusted by loosening the nut 100, moving the pointers 93 and 98 to appropriate positions on the dial 18 and retightening the nut 100.

As pointed out before, when the cam follower 75 is on the raised portion of the cam the thermostat will be adjusted to maintain the lower of the two temperature settings. When the pointers 93 and 98 are adjusted so that the cam disks 85 and 88 are in coincidence then the intermediate disks 86 and 87 will also be in coincidence therewith and the instrument will be adjusted to provide the minimum possible time of reduced temperature. In the illustrated construction it will amount to approximately six hours. The maximum possible time of reduced temperature adjustment is provided when the cam disks are adjusted to the position shown in Figure 4. It will be noted that the various projections and radial openings in the cam disk have caused the several disks to be equally spaced and to provide an effective raised cam periphery that is somewhat more than twice the raised periphery provided when the various disks are coincident. The interlocking means provided between the various cam disks assures that in any adjusted position of the pointers, the

top cam disk 88 and the bottom cam disk 85 will determine the limits of the effective raised portion of the cam, but the relative positions of the intermediate cam disks will be definitely fixed only at the minimum and maximum possible cam adjustments.

In Figure 1 the cam 23 has been adjusted to lower the temperature setting to that determined by the arm 61 at eleven o'clock. Since it is now approximately a quarter to one as indicated by the clock hands, the cam, which is rotating counterclockwise, has raised the roller 76 of the cam follower 75 to raise the extension 78 away from the abutment screw 79 and tension the spring 81 to move the member 54 to a position determined by the temperature setting arm 61. It should be pointed out here that the spring 81 is somewhat stronger than the resilient blade 41 and moves the contacts to open position through the bimetal element 45. However, when the room temperature is reduced sufficiently the bimetal element 46 will permit the resilient blade 41 to reclose the contacts.

Although the pointer 93 is not visible in Figure 1 it is evident from the position of the cam segments that they have been adjusted to provide approximately eight hours of reduced temperature. Hence at about seven o'clock the roller 76 of the cam follower 75 will ride off the high surface of the cam and will be moved in a clockwise direction as the roller 76 moves down the inclined surface of the upper cam disk. The pin 57 on the member 54 will remain in engagement with the night temperature setting arm 61 until the extension 78 of the cam follower engages the abutment screw 79 on the lever 54. Further clockwise movement of the cam follower will permit the pin 57 to be moved from the arm 61 to the day temperature adjusting arm 60 due to the bias of the resilient blade 41. The parts will then be in the position shown in Figure 3. If the room temperature is sufficiently low, after the contacts have been moved to closed position by the bias of the blade 41 the bimetal element 46 may be out of engagement with the abutment 47 of the contact arm 42 and therefore will exert no clockwise force on the members 54 and 55 and the pin 57 may therefore be in engagement with neither of the arm 60 nor 61. Contacts will remain closed then until the room temperature rises sufficiently to separate the legs of the U-shaped bimetal element 46 causing the member 54 to raise the pin 57 into engagement with the day temperature adjusting arm 60. Engagement of the pin 57 and the arm 60 enables the element 46 to exert a thrust to open the contacts.

On continued counterclockwise movement of the cam the roller 76 of the cam follower 75 will be engaged by the inclined surface of the lower cam disk 85 to rotate the cam follower in a counterclockwise direction and the pin 57 on the member 54 will start to move toward the adjusting arm 61 as soon as the cam follower starts to move. After the pin 57 engages the arm 61 the cam follower extension 78 will leave the abutment screw 79, and the pin 57 will be maintained against arm 61 by the tension of the spring 81. In this position of the parts the bimetal element 45 acts against an abutment established by the member 54 and the spring 81 to overcome the resilient blade 41 in order to open the contacts.

While the arrangement for providing an adjustable high and low temperature setting and the cam structure for shifting between these two settings has been described in connection with a par-

ticular bimetal thermostat, it is obvious that other condition responsive means could be substituted without departing from the spirit of the invention. Instead of contacts operated by a thermostatic element it will be apparent that a control valve such as used in pneumatic thermostats might be substituted. Likewise, a volatile fill bellows might be substituted for the bimetallic element. Also, in the broader aspects of the invention, it is not essential that the device be used to control temperature, and a humidity responsive element might be substituted for a temperature responsive element where it is desired to maintain different humidity conditions at different times.

The various features of novelty of the invention can be put into practice in apparatus taking many different forms and it is to be understood, therefore, that the scope of the invention is to be limited only by the appended claims.

I claim as my invention:

1. In a control device, a base, condition responsive means having a first portion shiftable with respect to said base, a pair of adjustable stops limiting the range of possible shift of said condition responsive means, control means carried by said base and adapted to be actuated by a second portion of said condition responsive means at a condition value depending on the position of the first portion of said condition responsive means with respect to said base, a spring acting between said base and the second portion of said condition responsive means for biasing said condition responsive means to a position determined by one of said stops, and means for shifting said condition responsive means to a position determined by the other of said stops against the bias of said spring.

2. In a clock thermostat, a stationary contact, a contact movable with respect to said stationary contact between engaged and disengaged positions, a spring biasing said movable contact to one of its operative positions, a clock mechanism, a cam driven by said clock mechanism, a cam follower, a member movable between first and second positions, a bimetal element interconnecting said member and said movable contact and adapted to move said contact against the bias of said spring, and a strain release connection between said cam follower and said member.

3. In a clock thermostat, a stationary contact, a contact movable with respect to said stationary contact between engaged and disengaged positions, a spring biasing said movable contact to one of its operative positions, a clock mechanism, a cam driven by said clock mechanism, a cam follower, a pair of adjustable stops, a member movable between first and second positions determined by said stops, a bimetal element interconnecting said member and said movable contact and adapted to move said contact against the bias of said spring, and a strain release connection between said cam follower and said member.

4. In a clock thermostat, a stationary contact, a contact movable with respect to said stationary contact between engaged and disengaged positions, a spring biasing said movable contact to one of its operative positions, a clock mechanism, a cam driven by said clock mechanism, a cam follower, a pair of arms pivoted on the same axis and cooperating with a scale having temperature indicia thereon, a member movable between first and second positions determined by the positions of said arms, a bimetal element interconnecting

said member and said movable contact and adapted to move said contact against the bias of said spring, and a strain release connection between said cam follower and said member.

5. A clock thermostat comprising a base, a temperature sensitive switch carried on said base, a pair of adjusting arms, a member for adjusting the control point of said temperature sensitive switch, a clock driven cam and a cam follower connected to said member for shifting said member between positions determined by said arms, said cam comprising more than two similarly contoured overlying sections each of which is provided with interlocking means cooperating with adjacent disks to prevent separation of the effective raised edge thereof, said interlocking means also causing coincidence of said sections at one extremity of adjustment thereof.

6. In a clock thermostat, temperature sensitive controlling means, means for shifting the control point of said controlling means, a clock motor, a dial rotated by said motor, indicia of time on one surface of said dial, a composite cam comprising more than two of similarly contoured disks each having raised and reduced peripheral portions pivoted coaxially with said dial and lying on the side of said dial opposite said indicia, a pointer on the indicia side of said dial rotatable with one of said disks, a pointer on the indicia side of said dial rotatable with another of said disks, interlocking means acting between adjacent disks to prevent separation of the raised portions of said disks, and a cam follower operatively connected to said shifting means.

7. In a clock thermostat, temperature sensitive controlling means, means for shifting the control point of said controlling means, a clock motor, a dial rotated by said motor, indicia of time on one surface of said dial, a composite cam comprising a plurality of similarly contoured disks each having a raised and a reduced peripheral portion pivoted coaxially with said dial and located on the side of said dial opposite said indicia, a first pointer on the indicia side of said dial rotatable with the cam disk nearest said dial but slidable axially with respect thereto, a second pointer on the indicia side of said dial rotatable with the cam disk farthest from said dial but slidable axially with respect thereto, means for forcing said pointers and said cam disks against said dial to provide a unitary structure rotatable by said clock motor, and a cam follower cooperating with the raised portions of said cam disks operatively connected to said shifting means.

8. In a clock thermostat, temperature sensitive controlling means, means for shifting the control point of said controlling means, a clock motor, a dial rotated by said motor, indicia of time on one surface of said dial, a composite cam comprising a plurality of similarly contoured disks each having a raised and a reduced peripheral portion pivoted coaxially with said dial and located on the side of said dial opposite said indicia, a first pointer on the indicia side of said dial rotatable with the cam disk nearest said dial but slidable axially with respect thereto, a second pointer on the indicia side of said dial rotatable with the cam disk farthest from said dial but slidable axially with respect thereto, means for forcing said pointers and said cam disks against said dial to provide a unitary structure rotatable by said clock motor, interlocking means acting between adjacent cam disks to prevent circumferential separation of the raised por-

tions thereof, and a cam follower cooperating with the raised portions of said cam disks operatively connected to said shifting means.

9. An adjustable cam assembly comprising a rotatable dial, indicia of time on one surface of said dial, a composite cam comprising a plurality of similarly contoured disks each having a raised and a reduced peripheral portion pivoted coaxially with said dial and located on the side of said dial opposite said indicia, a first pointer on the indicia side of said dial rotatable with the cam disk nearest said dial but slideable axially with respect thereto, a second pointer on the indicia side of said dial rotatable with the cam disk farthest from said dial but slideable axially with respect thereto, and means for forcing said pointers and said cam disks against said dial to provide a unitary rotatable structure.

10. In a clock thermostat, temperature sensitive controlling means, means for shifting the control point of said controlling means, a clock motor, a dial rotated by said motor, indicia of time on one surface of said dial, a composite cam comprising a plurality of similarly contoured disks each having a raised and a reduced peripheral portion pivoted coaxially with said dial and located on the side of said dial opposite said indicia, a first pointer on the indicia side of said dial rotatable with the cam disk nearest said dial but slideable axially with respect thereto, a second pointer on the indicia side of said dial rotatable with the cam disk farthest from said dial but slideable axially with respect thereto, means for forcing said pointers and said cam disks against said dial to provide a unitary structure rotatable by said clock motor, interlocking means between said cam disks to prevent circumferential separation of the raised portions thereof, said interlocking means also causing alignment of all of said disks when said pointers are adjusted to a predetermined position for providing an effective composite cam surface having a minimum raised portion equal to the raised portion of one of said disks, and a cam follower cooperating with the raised portions of said cam disks operatively connected to said shifting means.

11. In a clock thermostat, a base, a thermostatic switch, a member pivoted on said base and connected to said switch for adjusting the control point of said switch, a pair of abutments for limiting pivotal movement of said member, a cam follower pivoted on said base coaxially with said member, cooperating abutments on said cam follower and said member, a spring biasing the abutment on said cam follower into engagement with the abutment on said member and a clock driven cam for positioning said cam follower.

12. In a clock thermostat, a base, a thermostatic switch, a first member pivoted on said base for adjusting the control point of said switch, a second member pivoted on said base coaxially with said first member, means for adjusting the angular relation between said members, a pair of abutments adjustable with respect to said base adapted to engage said second member for limiting pivotal movement of said second members, a cam follower pivoted coaxially with said members and having an abutment adapted to engage one of said members, a spring biasing said cam follower to a position determined by the position of said members, and a clock driven cam for positioning said cam follower.

13. In a clock thermostat, temperature sensitive controlling means, means for shifting the control point of said controlling means, a clock

motor, a dial rotated by said motor, indicia of time on one surface of said dial, first and second pointers cooperating with said indicia, first and second cam disks on the opposite side of said dial, a member extending through said dial and interconnecting said first cam disk and said first pointer, a member extending through said dial and interconnecting said second cam disk and said second pointer, a third cam disk intermediate said first and second disks, said cam disks, said pointers and said members being rotatably adjustable with respect to said dial about the pivotal axis of said dial, said cam disks being similarly contoured and having extended and reduced arcuate peripheral portions, interlocking means between adjacent cam disks preventing separation of the extended peripheral portions of said disks, said interlocking means also causing coincidence of all of said cam disks at one relatively adjusted position of said pointers, a cam follower adapted to engage the peripheries of said cam disks, and a linkage between said cam follower and said shifting means.

14. In a clock thermostat, temperature sensitive controlling means, means for shifting the control point of said controlling means, a clock motor, a dial rotated by said motor, indicia of time on one surface of said dial, first and second pointers cooperating with said indicia, first and second cam disks on the opposite side of said dial, a member extending through said dial and interconnecting said first cam disk and said first pointer, a member extending through said dial and interconnecting said second cam disk and said second pointer, a third cam disk intermediate said first and second disks, said cam disks, said pointers and said members being rotatably adjustable with respect to said dial about the pivotal axis of said dial, said cam disks being similarly contoured and having extended and reduced arcuate peripheral portions, the raised portion of each cam disk including an angle of less than one hundred and twenty degrees, interlocking means between adjacent cam disks preventing separation of the extended peripheral portions of said disks, said interlocking means also causing coincidence of all of said cam disks at one relatively adjusted position of said pointers, a cam follower adapted to engage the peripheries of said cam disks, and a linkage between said cam follower and said shifting means.

15. In a clock thermostat, a base, a thermostatic switch, a pivot post mounted on said base, a first member pivoted on said post for adjusting the control point of said switch, a second member pivoted on said post, means for adjusting the angular relation between said members, a pair of abutments adjustable with respect to said base adapted to engage said second member to limit pivotal movement of said second member for determining the control point of said switch, a cam follower pivoted on said post and having an abutment adapted to engage one of said members, a spring biasing said cam follower toward a position determined by the position of one of said members, and a clock driven cam for positioning said cam follower.

16. In a clock thermostat, temperature sensitive controlling means, means for shifting the control point of said controlling means, a clock motor, a dial rotated by said motor, indicia of time on one surface of said dial, first and second pointers cooperating with said indicia, first and second cam disks on the opposite side of said

dial, a member interconnecting said first cam disk and said first pointer, a member interconnecting said second cam disk and said second pointer, a third cam disk intermediate said first and second disks, said cam disks, said pointers and said members being rotatably adjustable with respect to said dial about the pivotal axis of said dial, said cam disks being similarly contoured and having extended and reduced arcuate peripheral portions, interlocking means between adjacent cam disks preventing separation of the extended peripheral portions of said disks, said interlocking means also causing coincidence of all of said cam disks at one relatively adjusted position of said pointers, a cam follower adapted to engage the peripheries of said cam disks, and a linkage between said cam follower and said shifting means.

17. In a clock thermostat, temperature sensitive controlling means, means for shifting the control point of said controlling means, a clock motor, a dial rotated by said motor, indicia of time on said dial, first and second pointers cooperating with said indicia, first and second cam disks, a member interconnecting said first cam disk and said first pointer, a member interconnecting said second cam disk and said second pointer, a third cam disk intermediate said first and second disks, said cam disks, said pointers and said members being rotatably adjustable with respect to said dial about the pivotal axis of said dial, said cam disks having arcuate extended peripheral portions of substantially identical configuration, interlocking means between adjacent cam disks preventing separation of the

25

30

35

extended peripheral portions of said disks, said interlocking means also causing coincidence of the extended portions of all of said cam disks at one relatively adjusted position of said pointers, a cam follower adapted to engage the peripheries of said cam disks, and a linkage between said cam follower and said shifting means.

18. An adjustable cam assembly comprising a rotatable dial having indicia thereon, a composite cam comprising a stack of disks pivoted coaxially with said dial, a first pointer cooperating with said indicia and rotatable with a first one of said disks, a second pointer cooperating with said indicia and rotatable with a second one of said disks, a third disk intermediate said first and second disks, each of said disks having a reduced peripheral portion and an arcuate extended peripheral portion, and interlocking means between adjacent disks preventing separation of the extended peripheral portions of adjacent disks, said interlocking means also causing coincidence of the extended portions of said disks at one relatively adjusted position of said pointers.

CARL G. KRONMILLER.
